EDGAR E. GREVE, OF BELLEVUE, PENNSYLVANIA, ASSIGNOR TO OIL WELL SUPPLY COMPANY, OF PITTSBURGH, PENNSYLVANIA, A CORPORATION OF PENNSYLVANIA

TEMPER SCREW

Application filed July 2, 1925. Serial No. 41,095.

This invention is for an improvement in temper screws employed in connection with earth drilling apparatus.

Temper screws are hung from the walking beam of a drilling outfit and provide the connection between the drilling cable, on which the tool string is carried, and the walking beam. It is adjustable so that the operator may regulate the length of the drilling line 10 in accordance with the progress being made in drilling.

One of the main objections to present types of temper screws is that the yoke from which the cable clamp is suspended, is free to swivel. 15 As the drilling cable is usually made of wire rope, this freedom of the clamp to swivel decreases the advantages obtained by the "lay of the line", that is, the normal, desired position of the cable. Furthermore, such 20 swiveling of the line is dangerous.

According to the present invention it is proposed to provide a construction wherein such swiveling is eliminated and wherein neither the screw nor the body which carries 25 the screw is rotated.

Further objects of the invention are to provide a temper screw of rugged construction which may be assembled in a practical manner and which may be conveniently operated; and to provide in a device of this kind, removable thread liners which are not liable to work loose in operation.

The nature of the invention and its objects and advantages may be understood by reference to the accompanying drawings in which a preferred embodiment of the inventions is illustrated. In the drawings,

Fig. 1 is a side elevation of the assembly.

Fig. 2 represents a vertical section through 40 the operating part of the device.

Fig. 3 is a transverse section in the plane of line III—III of Fig. 2.

Fig. 4 is a view generally similar to Fig. 2 of a modified form of thread liner.

Fig. 5 is a transverse section in the plane of line V—V of Fig. 4.

Referring to the drawings, 5 designates the temper screw body having a head 6 at its upper end for engagement with a walking beam, such head being retained in place by

a nut 7 screwed onto the upper end of the body. The lower end of the body 5 is bifurcated to provide spaced apart reins 5^a on the lower end of each of which is a flange 8.

The temper screw itself is designated 9, 55 and is received in the space between the spaced apart reins 5^a. Retained on the upper end of the temper screw by means of nut 10, and slidably guided by the reins, is a cross bar 11 to which an elevating line, not shown, 60 may be attached in accordance with the usual practice.

Above and below the flanges 8 are ball cages 12 and 13, respectively, providing a swiveled support for a divided nut, indicated 65 generally as 14. This nut is formed of two longitudinally divided sections 14^a and 14^b. Section 14^a may have lugs 15 thereon projecting into correspondingly positioned notches in the section 14^b for holding the sections 70 against relative longitudinal movement. The upper ends of each of the sections is enlarged to enclose the ball cages, as shown, thus providing the swiveled suspension referred to.

The nut 14 is contracted between its enlarged upper end and its lower end, and embracing this contracted portion is a yoke 16 from one side of which projects a handle 16^a that has its innermost end threaded through 80 the yoke into nut section 14^b. Diametrically opposed to the handle 16^a is a screw 17 threaded through the yoke and connected to nut section 14^a through a swivel connection 18. This screw serves as a handle, similar to 16^a, and 85 also provides a means by which the nut sections may be moved toward and from each other by rotation thereof. For rotating screw 17, a transverse handle 19 may be fixed thereon.

Set into the back of the opposed semicircular cavities in the adjacent faces of the sections 14^a and 14^b are semi-circular thread liners 20. These are provided with suitable ribs, such as 20^a that are received in suitable 95 recesses in the respective nut sections for holding the thread liners against relative longitudinal movement or displacement. They may be removably held in place in any suitable manner, as by screws 21 that pass through 100

the respective nut sections into the liners, as best shown in Fig. 2. These screws may be directly in line with handle 16^a and screw handle 17 so that they cannot be removed without first removing handles 16^a and 17. This protects the thread liners against accidental removal by reason of the screws working loose.

In the arrangement shown in Figs. 4 and 10, I have shown a slightly modified form of thread liner in a construction otherwise similar to that described. The parts of the structure corresponding to Figs. 1 and 2 have been designated by similar reference numerals, but 15 the thread liners are indicated at 22. Each of them has an extension 22^a of a hook-like form at each end that engages over a rib at each end of the nut sections, and bolts 23 in these extensions serve to secure the liners in 20 place. Being of semicircular form, they can be readily slipped into the nut sections.

The lower end of the screw itself projects below the temper screw and terminates in a body button 9^a. Below the nut and above the 25 button is a cross bar or clamp support 24, this is non-rotatable on the screw, a key 25 being shown for connecting the cross bar to the lower end of the screw. In the opposite ends of the cross bar are notches 26 into which 30 links 27 of the usual type, (shown in dotted lines) are fastened. These links support the cable clamp, not shown.

With this arrangement, it will be seen, that the sectional nut 14 may be rotated by means 35 of the projecting handles to raise or lower the screw and that there can be no rotative movement between the screw and the temper screw body. The cross bar 11, of course, prevents the screw from turning in the body 40 while permitting of the sliding movement thereof. At the same time, the nut 14 may be easily operated, especially by reason of the ball bearings at 12 and 13.

While I have illustrated a preferred form 45 of my invention, it will be understood that such form is to be considered as merely illustrative of the invention.

I claim as my invention:

1. A temper screw including a body having 50 reins formed with flanged ends, a screw slidably retained in the body, a divided nut on the screw, the sections of said nut surrounding and being swiveled on the flanges of the reins and operable for adjustably moving the screw in the body, a clamp means to unitarily secure the nut sections together, and means carried by said clamp means for adjusting the nut sections.

2. A temper screw including a slidably connected body and screw, said body having 60 reins formed with flanged ends, a divided nut, the sections of said nut surrounding and being swiveled on the flanges of the body and having a lower portion in screw-threaded engagement with the screw for adjustably mov-

ing the latter, a clamp embracing the sections of the nut, means for actuating the nut, and detachable thread liners carried by the lower portion of the nut.

3. A temper screw including a body, a screw 70 slidably retained in the body, a divided nut swiveled on the body and engaging the screw for effecting a sliding movement thereof, said nut having an enlarged upper thrust-bearing receiving portion surrounding and 75 substantially directly supported on the lower end of the body and a lower portion having threads therein to cooperate with the screw, said nut being engageable and disengageable with the body when the sections thereof are 80 divided, a clamping yoke embracing the sections of the nut, and said screw having a cross bar at one end thereof from which a cable clamp may be hung.

4. A temper screw including a body having 85 an integral flange at its lower end, a screw slidably and non-rotatably connected with the body, a nut rotatable and non-slidable on the body and engaging the screw for adjustably connecting the body and screw, said nut having extended lateral surfaces 90 above and below said flange, bearings on the body above and below the flange arranged in contact with said surfaces, and said nut being sectional to permit engagement with the flange and reception of said bearings.

5. A temper screw including a body having 95 a head at its upper end and having its lower end divided to provide a pair of parallel reins, a flange on the ends of the reins 100 at the lowermost end of the body, a screw associated with the body and having its upper end received between the reins, a crosshead on the screw slidably engaging the reins for 105 slidably guiding said screw in the body and holding it against rotation with respect thereto, a nut on the body engaging the screw, said nut being comprised of two vertically divided sections having an upper portion rotatably fitted over the flange at the lower end 110 of said body, and a lower portion having threads therein to cooperate with the screw, and a clamping yoke embracing the lower part of the nut.

6. The combination with a temper screw 115 device including a body, and a screw slidable and non-rotatable with respect to the body, of a nut for adjustably connecting the screw and the body, said nut comprising co-operating vertical sections having upper ends engaging a flange on the said body to provide a swiveled suspension for the nut, said sections having lower portions in which are 120 thread liners, a clamping yoke embracing the nut sections and non-rotatable with respect thereto, and an operating screw on the yoke.

7. The combination with a temper screw 125 device including a body, and a screw slidable and non-rotatable with respect to the body, of a nut for adjustably connecting the screw 130

and the body, said nut comprising co-operating vertical sections having upper ends engaging a flange on the said body to provide a swiveled suspension for the nut, said sections having lower portions in which are thread liners, a clamping yoke embracing the nut sections, a handle on the yoke passing therethrough and engaged in one of the nut sections to hold the yoke against rotative movement on the nut, and a second rotatable handle on the yoke threaded through the yoke and bearing against another section of the nut.

8. The combination with a temper screw device including a body, and a screw slidably and non-rotatably connected with the body, of a sectional clamping nut having a swiveled suspension on the body and projecting below the lowermost end of the body, removable thread liners in the projecting portion of the sectional nut and engaging said screw, said liners having flanged upper and lower ends interfitting with co-operating flanges on the nut sections, bolts for holding the liners in place, a clamping yoke embracing the sectional nut and non-rotatably secured thereto, and operating means on the yoke for clamping and loosening the nut sections:

In testimony whereof I affix my signature.
